Primary Examiner — Catherine Tuttle*(74) Attorney, Agent, or Firm* — Bush Intellectual Property Law; Kenneth M. Bush**CLAIM**

I claim the ornamental design for a balancing amusement apparatus, as shown and described.

DESCRIPTION

FIG. 1 is a left front perspective view of a balancing amusement apparatus showing my new design with its top portion in a first orientation;

FIG. 2 is a front elevation view thereof in the first orientation, the rear elevation view being identical to the front elevation view;

FIG. 3 is a left side elevation view thereof in the first orientation, the right side elevation view being identical to the left side elevation view;

FIG. 4 is a top plan view thereof in the first orientation;

FIG. 5 is a bottom plan view thereof in the first orientation;

FIG. 6 is a left front perspective view thereof in a second orientation;

FIG. 7 is a front elevation view thereof with its top portion in a second, inverted orientation, the rear elevation view being identical to the front elevation view;

FIG. 8 is a left side elevation view thereof in the second orientation, the right side elevation view being identical to the left side elevation view;

FIG. 9 is a top plan view thereof in the second orientation; and,

FIG. 10 is a bottom plan view thereof in the second orientation.

In FIGS. 4 and 9, the broken lines illustrating numbers are for illustrative purposes only and form no part of the claimed design. In FIGS. 1-3 and 6-8, the balance pole has been broken with wavy lines to indicate indefinite length.
